UNITED STATES PATENT OFFICE.

CHARLES W. WALLER, OF CHICAGO, ILLINOIS.

ALARM-CLOCK.

1,366,983.

Specification of Letters Patent.

Patented Feb. 1, 1921.

Application filed August 22, 1919. Serial No. 319,222.

To all whom it may concern:

Be it known that I, CHARLES W. WALLER, a citizen of the United States, and a resident of Chicago, in the county of Cook and 5 State of Illinois, have invented certain new and useful Improvements in Alarm-Clocks, of which the following is a specification.

My invention is an improvement in alarm clocks, and has for its object to provide 10 mechanism for use in connection with alarm clocks for converting said clocks into noiseless alarms, whose sound will carry only to the one person whom it is desired to waken.

In the drawings:

15 Figure 1 is a perspective view showing the clock in use.

Fig. 2 is a front view of the clock with parts broken away.

The present embodiment of the invention 20 is shown in connection with a clock 1 of ordinary construction, the said clock having a hammer 2 controlled by the clock movement for oscillating the same at predetermined times. The usual bell is re- 25 placed by a diaphragm 3 of any suitable material, which is arranged within an extension 4 from the clock case. This extension has a nipple 5 at the opposite side of the diaphragm from the hammer, and a 30 tube 6 of rubber or the like has one end connected with the nipple. The other end of the tube is connected with the body of a tubular fork 7, each arm of the fork having an ear piece or tube 8. In use, the 35 clock is arranged at the bed side, upon a suitable stand 9, and the tube 6 leading from the extension is passed over the head board of the bed 10 to the person whom it is desired to waken.

40 The ear pieces are engaged within such persons ears as shown, and it will be obvious that when the alarm goes off, which will be at the time appointed, the sound

vibrations will be carried by the flexible tube directly to the users ears, and the clock 45 will be practically noiseless to any other but the user.

I claim:

1. In combination with a clock having an alarm hammer and a diaphragm with 50 which the hammer coöperates and an extension chamber in connection with the clock case, said diaphragm being arranged transversely of the chamber, and the hammer being within the chamber, said extension 55 having a nipple on the opposite side of the diaphragm from the hammer, and conducting mechanism for the sound vibration connected with the nipple, said conducting mechanism comprising a flexible tube 60 branched at the end remote from the clock and having ear pieces for the purpose specified.

2. In combination with a clock having an alarm hammer and a diaphragm with which 65 the hammer coöperates and an extension chamber in connection with the clock case, said diaphragm being arranged transversely of the chamber, and the hammer being within the chamber, said extension having a nipple on the opposite side of the diaphragm from the hammer, and conducting mechanism for the sound vibration connected with the nipple. 70

3. In combination, a clock having an 75 alarm and an extension chamber in which the alarm is arranged, an ear piece, and a flexible connection leading from the chamber to the ear piece.

4. In combination, a clock having an extension chamber provided with a diaphragm and an alarm whose hammer is in the chamber and coöperates with the diaphragm, an ear-piece, and a flexible hollow connection leading from the chamber to the ear-piece. 80 85

CHARLES W. WALLER.
